UNITED STATES PATENT OFFICE.

OLIVER L. SCOTT, OF SAN FRANCISCO, CALIFORNIA.

CARBURETER.

1,301,610.

Specification of Letters Patent. Patented Apr. 22, 1919.

Application filed February 15, 1917. Serial No. 148,734.

To all whom it may concern:

Be it known that I, OLIVER L. SCOTT, a citizen of the United States, residing at the city and county of San Francisco and State 5 of California, have invented new and useful Improvements in Carbureters, of which the following is a specification.

This invention relates to that class of carbureting apparatus in which gas or air is 10 conducted through serpentine passages in contact with a volatile hydrocarbon liquid, the said liquid being caused to rise by capillary action through wicks of fabric or other fibrous material, so as to provide a comparatively 15 large surface exposed to vaporization.

The present invention comprises several improvements, to-wit: a novel mounting of superposed pans inclosed by a casing; a 20 serpentine arrangement of wicks suspended in a fuel well formed in each pan; a plurality of suspended wicks each inclosed in such a manner that the fuel is always drawn from the bottom of each well; and an improved 25 pan construction and other features hereinafter to be described.

The invention also comprises details of construction which will be more fully explained by reference to the accompanying 30 drawings, in which—

Figure 1 is a side elevation of the carbureter partly in section.

Fig. 2 is a plan section on line 2—2 of Fig. 1.

Fig. 3 is a cross section on line 3—3 of Fig. 1.

Fig. 4 is a perspective view, partly broken away, showing one of the pans.

Referring to the drawings in detail, A 40 indicates a rectangular shaped casing constructed of sheet iron or like material, interiorly of which is mounted a plurality of superposed pans 2, 3, 4, 5 and 6. Each pan is constructed substantially as shown in Fig. 45 4 and comprises a bottom 7, a pair of side sections 8, a front end section 9, and a rear end section 10; the sides being secured together by inturning the upper edges, as shown at 17, and fitting same in channels 50 formed in a cover member 11 preferably constructed of wood, or the sides may be secured together merely by tacking the upper edges, as at 12, to the cover. One end of the cover is flush with the front end 9 55 and as this end is merely carried half way up, as shown at 13, an intake opening 14 is

formed through which air will pass, as hereinafter described. The other end of the cover is cut off to form a top outlet 15, between the end section 10 and the cover, and 60 the cover is also provided as a means for supporting a plurality of wicks, such as shown at 16.

The wicks, referring to Fig. 2, are disposed parallel with relation to each other 65 and crosswise of the pan to form a serpentine passage, such as indicated by the arrows. The upper edge of each wick is tacked to the cover section 11 and the length is sufficient to extend approximately to the 70 bottom 7 of the pan. Surrounding each wick, and suitably secured thereto, is an inclosing member 18, which consists of a piece of tin. This is clamped or otherwise secured to each wick and is sufficiently long 75 to extend a little above the highest oil level obtained in each pan. The lower end of each wick projects below the inclosing member 18 and all oil absorbed by the wicks is drawn from the bottom of the pans. This 80 is an important feature when it is considered that practically all gasoline sold contains more or less distillate or low gravity oils which will not readily evaporate. Each pan would, therefore, gradually accumulate 85 a considerable amount of low gravity oil, if the wicks were not inclosed as here shown, as the lighter oils would be quickly drawn up through the wicks while the low gravity oil would collect as a residue on the bottom. 90

By inclosing each wick, as shown, it can readily be seen that all oil is drawn from the bottom. The low gravity oil which would otherwise accumulate is, therefore, drawn up with the lighter oil and is given 95 more chance to evaporate than would otherwise be the case.

In actual operation, referring to Fig. 1, it will be seen that a plurality of superimposed pans are employed. The first or 100 lowermost pan is placed in the bottom of the casing and is here secured in any suitable manner; the second pan 3 is then placed on top of the lowermost pan, with its rear end wall 10 in engagement with the intake 105 side of the casing; the third pan 4 is placed in the opposite direction; and the pans 5 and 6 are also reversed. Air entering through a pipe 19 will, therefore, pass between the wicks in the lowermost pan and 110 then escape through the top outlet 15 and enter the front inlet 14 of the next pan;

2
then passing through and between the wicks in said pan and out through the top outlet 15 from where it enters the front end inlet 14 of the next pan. The air is thus caused 5 to pass back and forth through each pan in successive order, and as each pan contains a great wick area it can readily be seen that a comparatively high percentage of volatile hydrocarbon gas is absorbed before it finally 10 escapes through the outlet pipe 20.

The casing is provided with a filling funnel 21, through which the gasoline is poured. The gasoline thus admitted will first fill the upper pan and will then overflow 15 the end section 9, which determines the maximum level of each pan, down into the pan directly under. This, when filled to the height of its end section 9, again overflows and each pan will in turn overflow until 20 the lowermost pan has been filled; the level in the lowermost pan being determined by a gage glass, such as shown at 22. Each pan is provided with a drain consisting of a nipple 23, a T-fitting 24, a drain valve 25 25 and a closing plug 26. The plugs 26 and the height of the fittings 24 are such that removal of any plug 26 permits the oil level in any pan to be determined. Also the valve 25 permits draining of any individual pan, if it is found that too much low gravity oil has accumulated.

Air may be forced through the casing by a compressor fan, or any other suitable means, and the discharge pipe 20 may be 35 directly connected with the service piping of a dwelling or may be directly connected with a gasometer for storage and future use; all such piping carrying gas, however, being preferably placed on an incline to 40 permit drainage back to the casing of any gas which may have re-condensed.

The carbureter as a whole is simple and substantial in construction and has in actual practice been found to be very efficient, as 45 it not only presents a large saturated wick area through and between which the air must pass before it can escape, but it has also proven much more efficient than any carbureter heretofore used as comparatively little residue is obtained.

For the purpose of preventing the wicks from waving or blowing entirely out of the gasoline when a comparatively strong current of air is being passed through the carbureter four tie rods 30 have been provided in connection with each set of wicks. The two outside rods abut against the ends of the pans while all four rods pass through the lower ends of the wicks and act as 55 weights or spacers which hold the lower ends in spaced relation and prevent any in-

dividual wick or set of same from blowing out, as previously mentioned.

For the purpose of preventing the sides of the casing from bulging out when air is being forced through the casing a pair of strips 29 has been secured to each pan cover section. The outer ends of these strips are turned down, as at 31, and secured to the inner sides of the casing are vertically spaced pairs of opposing strips 32 which have their upper edge portions inwardly offset to provide tracks over which the downturned ends 31 engage to thereby secure the sides with relation to the pans and prevent bulging. The tracks or guides, together with the strips 29, furthermore, provide means for supporting each individual pan within the casing independent of the other. These strips 32 are suitably secured 80 to the sides of the casing, as by spot welding.

The materials and finish of the several parts of the carbureter are such as the experience and judgment of the manufacturer 85 may dictate.

I wish it understood that various changes in form, proportions and minor details of construction may be resorted to within the scope of the appended claim and that I do 90 not wish to limit myself to the specific design and construction here shown.

Having thus described my invention, what I claim and desire to secure by Letters Patent is—

In a carbureter, a casing having spaced inlet and outlet openings, vertically spaced pairs of opposing strips secured to the inner side walls thereof and having their upper edge portions inwardly offset, a plurality of closed oil pans each having an air inlet in one end and an outlet in the opposite end communicating with the inlet of a next adjacent pan whereby a current of air will follow a zig-zag course through the 105 pans for contact with the oil therein, the inlet of the first pan communicating with the inlet opening of the casing and the outlet of the last pan communicating with the outlet opening of the casing, and strips 110 transversely arranged on the pans and provided with downturned ends engaging over the inwardly offset upper edges of the first strips to prevent bulging of the side walls of the casing.

In testimony whereof I have hereunto set my hand in the presence of a subscribing witness.

OLIVER L. SCOTT.

Witness:

JOHN H. HERRING.
